UNITED STATES PATENT OFFICE.

SIMEON B. CURTIS, OF SPRINGFIELD, ILLINOIS.

MECHANICAL MOVEMENT.

SPECIFICATION forming part of Letters Patent No. 530,638, dated December 11, 1894.

Application filed September 21, 1893. Serial No. 486,096. (No model.)

To all whom it may concern:

Be it known that I, SIMEON B. CURTIS, a citizen of the United States, residing at Springfield, in the county of Sangamon and State of Illinois, have invented a certain new and useful Mechanical Movement, of which the following is such a full, clear, and exact description as will enable those skilled in the art to which it pertains to make and use my said invention.

The purpose of my invention is to provide simple and effective means for converting rotary motion into reciprocating motion.

My invention is adaptable to and may be applied on any machine in which it is desired to convert rotary into reciprocating motion.

My invention consists of certain novel features of construction and combinations of mechanism illustrated in the annexed drawings, to which reference is hereby made, and hereinafter fully described and specifically claimed.

In the drawings—Figure 1—is a side elevation of the complete machine. Fig. 2—is a vertical transverse section on the line 2 of Fig. 1. Fig. 3—is a horizontal section on the line 3 of Fig. 2. Fig. 4—is an enlarged detached perspective view of the rotary arm and shows the pivotal pawl in position on the arm. Fig. 5—is an enlarged detached combined perspective and sectional view of a part of the left hand channeled wheel D and shows the position and the form of the channel d, one of the cams d', and one of the ledges d'' in said wheel. Fig. 6—is an enlarged detached combined and perspective and sectional view of a part of the right hand channeled wheel D', and shows the position and form of the channel d, the cams and the ledges in that wheel.

Similar letters indicate like parts in all of the views.

The base A is provided with integral standards a. At the top of the standards a are journal boxes a'. A shaft B revolves in the boxes a'. A crank C, (or other suitable means such as a pulley or cog gear for example) is secured to one end of and serves to rotate the shaft. The bevel cog wheels D and D' which will hereinafter be described in detail are supported and are loose on the shaft B.

The rotating arm E is secured to the shaft B between the wheels D and D' and turns with

the shaft. A pawl F is pivotally supported in a slot e on a transverse pin e' in the end of the arm E.

55

The base A is pierced by a vertical central hole a² through which the vertical shaft G passes. The upper end of the shaft G is squared and supports a bevel cog-pinion H which meshes with and is driven alternately right and left by the bevel cog wheels D and D', respectively. If preferred the squared part of the shaft G may be dispensed with and a shaft round in its entire length may be used without departing from my invention. An adjustable collar g serves to support the shaft G on the base A and permits such adjustment of the pinion H relative to the wheels D and D' as will cause the pinion to mesh properly with said wheels.

70

In the inner face of each of the wheels D and D' is an annular channel or way d adapted to receive the reduced ends f or f' as the case may be, of the pivotal pawl F. At one or more points of the channel d are situated deflecting cams or wedges d' which serve to actuate the pivotal pawl F as hereinafter explained. Adjacent to the cams d' are shoulders or ledges d'' with which the points f engage to alternately turn the wheels D and D'. 80

75

The wheels D and D' are exactly alike except that one has right hand cams and ledges, and the other has left hand cams and ledges, that is to say:—when viewed from the front of the wheel D, the cams d' in that wheel incline to the right as shown in Fig. 5; and when viewed from the front of the wheel D', the cams in that wheel incline to the left as shown in Fig. 6, but when the wheels are in place face to face on the shaft B, the cams in both wheels incline and the ledges in both wheels face in a direction contrary to the rotative direction of the shaft B, so that when the shaft is turned the pawl F alternately engages with the ledges in the wheels D and D'. 95

85

When the several parts of the mechanism are properly assembled and adjusted one end f of the pivotal pawl F fits loosely and moves in the channel of the wheel D, while the other end of the pawl fits loosely and moves in the channel in the wheel D'.

100

Any suitable mechanism may be connected in any convenient manner with the lower projecting end of the alternating shaft G as for

example the beater of a churn, or the rubber of a washing machine, &c.

I do not restrict myself to the application of my invention to machines of any particular class as it may obviously be applied to a great variety of machines.

The operation of the mechanism is as follows:—The crank C is turned to the left thereby turning the shaft B and the connected arm 10 E in the same direction. The arm E carries around with it the pawl F and the end f of the pawl runs freely in the channel d until the end f engages with the ledge d² thereby causing the wheel D to turn in the same direction as the shaft B and drive the pinion H to the left. The pinion being in mesh with the wheel D' drives the wheel D' to the right or in a direction contrary to the rotative direction of the shaft B until the end f' of the 15 pawl F running in the channel of the wheel D' rides on the cam d' in said wheel and is raised sufficiently to depress the opposite end f of the pawl and release it from engagement with the ledge d² and permit it to run in the 20 channel d of the wheel D and at the same time bring the end f' of the pawl into engagement with the ledge in the channel of the wheel D', thereby causing the wheel D' to change its direction of motion and revolve in 25 the same direction as the shaft B. The wheel D' then drives the pinion H to the right and the end f of the pawl F runs backward in the channel of the wheel D until that end of the pawl engages with the cam d' and raises the 30 end f of the pawl into engagement with the ledge d² of the wheel D and depresses the other end of the pawl and releases it from engagement with the ledge in the channel of the wheel D'. The wheel D then ceases to be 35 driven and again becomes the driver and so on continually.

I have shown and described two cams and two ledges on each of the wheels D and D', but a greater or less number of cams and 45 ledges may be used for the purpose of varying the frequency of the change of direction, without departing from my invention.

Having fully described my invention, what I claim as new, and desire to secure by Letters 50 Patent, is—

1. In a mechanical movement the means adapted to alternately engage parallel wheels with and disengage them from a supporting shaft on which said wheels turn, to wit:—a 55 suitably supported driving shaft, bevel cog wheels face to face, loose on said shaft, said wheels having channels in their inner faces

and having cams and ledges projecting into said channels, a suitably supported pinion meshing with both of said cog wheels, a rotating arm secured to the driving shaft between said wheels, and a pawl pivoted in the end of said arm, the ends of said pawl being adapted to run in the channels in said wheels, as set forth. 60

2. In a mechanical movement the combination of the base, the standards, on the base, the driving shaft supported and turning on said standards the means for rotating said driving shaft, the driven shaft supported on 70 and turning in the base, the parallel cog wheels loose on the driving shaft, said cog wheels having annular channels in their faces and having cams and ledges projecting into said channels, the arm secured to and turning with the driving shaft, the pawl pivotally supported in the end of said arm, the ends of said pawl being adapted to run in the channels in said wheels, and the pinions secured to the driven shaft and meshing with both of 75 the wheels on the driving shaft, as set forth.

3. A pawl for a mechanical movement, widened at its central part, adapted to turn on a pivot and having reduced ends adapted to run in channels; in combination with an 85 arm secured to a rotatable driving shaft and adapted to pivotally support said pawl, parallel cog wheels loose on said shaft provided with channels and having cams and ledges projecting into said channels, and a pinion 90 secured to the driven shaft and meshing with both of the cog wheels on the driving shaft, as set forth.

4. In a mechanical movement the combination of the base, the integral standards on the 95 base, the journal boxes on the standards, the rotatable driving shaft supported in the boxes, the parallel cog wheels loose on said shaft, provided with channels and having cams and ledges extending into said channels, the arm 100 between said wheels, secured to and turning with the driving shaft, the pawl on said arm adapted to run in channels, the driven shaft, the bevel cog pinion meshing with said wheels and connected with the driven shaft, and the 105 adjustable collar on the driven shaft, as set forth and for the purpose stated.

In witness whereof I have hereunto subscribed my name, at Springfield, Illinois, this 13th day of September, A. D. 1893.

SIMEON B. CURTIS.
